(57) **CLAIM**

The ornamental design for a camera mount, as shown and described.

DESCRIPTION

FIG. 1 is a front perspective view of the camera mount showing my new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a left side elevation view thereof; the right side elevation view being a mirror image thereof.

The broken lines shown in the drawings illustrate portions of the camera mount that form no part of the claimed design.
